UNITED STATES PATENT OFFICE.

DE ELBERT A. REYNOLDS, OF YONKERS, NEW YORK.

TELEPHONE RECEIVER.

Application filed February 19, 1925. Serial No. 10,166.

My invention relates to telephone and radio receivers.

One of the objects of my invention is to clarify the sounds emitted from the receiver by the use of a set of reeds arranged on the principle of a musical scale and vibrated by the transmitting electrical current.

Another object of this invention is to eliminate the vibrations of the usual diaphragm which in prior construction gives use to dissonant and other imposed sounds and to restrict the vibrations of the receiver solely to pure tones in consonance with the sounds originally imposed on the transmitter at the transmitting station. A vibrating diaphragm held in proximity to the tympanum of the ear for any considerable time becomes most annoying and nerve-racking, which is not the case where sound is conveyed to the tympanum by a set of musical reeds, as I have discovered from my invention.

A third object of this invention is to provide a sound-amplifying device specially adapted to radio reception with a more or less extended scale, each reed responding to the respective frequencies and thus reproducing with precision the original communication.

It is a recognized fact in telephone practice that the usual receiver delivers but a small fraction of the sound engendered at the transmitter. This shows the very low efficiency attained by the telephone receiver of the ordinary construction. Upon analysis I have found that this low efficiency is largely due to the stiffness of the ordinary ferro-type diaphragm employed in the receiver and that the energy of the electric current is largely consumed by the intermolecular friction or internal heat. The usual diaphragm is held at its periphery, and upon application of energy at its center, the resulting vibrations are produced at a great sacrifice of the electrical energy, and at best at a very imperfect reproduction of the sounds transmitted.

A further limitation in the usual diaphragm receiver is found in the relatively restricted range of resiliency of the metals employed in its construction. The limitations are imposed by the circular form of the diaphragm and tend to retard its vibrations, practically excluding the harmonics, and thereby destroying the timbre, modulation and quality that distinguishes one voice from

another. In the reed construction of my invention there is no retarding influence, since each reed responds to its cycle of vibrations and the reeds collectively transform each electrical wave into the respective component sound waves with the corresponding amplitudes of the respective transmitted sounds.

Perfect reproduction in a receiver at the lowest consumption of electrical energy is had by my invention under the conditions of the greatest freedom of the vibrating elements and with correct attuning to the frequencies of the electrical vibrations in harmony with the recognized scale of music.

In the preferred form of my invention, I have provided a bank or series of eight or more vibrating metallic reeds, each attuned to a note in the musical scale, thus covering one or more octaves and encompassing the range of the human voice in ordinary conversation. These reeds are preferably secured to a plate of non-magnetic material having grooved openings corresponding to the respective sizes and lengths of the reeds, with a heel-plate or bar resting firmly on one pole of the receiver to carry the magnetic flex to the series of reeds at or near the free ends of the reeds to attain full attraction by the opposing pole of the receiver and cause the free vibration of the reeds compositely forming the transmitted communication.

When employed as a sound amplifying receiver, the number of reeds may be increased to as many octaves as desired. The reeds may be stamped from a single piece of metal and attached to a bar forming a part of the magnetic circuit. It may also be found desirable to place the core of the voice-coil near the center of the set of reeds to cause the reeds to vibrate through a greater arc.

It will also be noted that it is thoroughly practical to build the plate or disc with the reeds attached, as an article of manufacture, in varied forms to fit any make or style of receiver by merely substituting my invention for the ordinary receiver diaphragm.

Further features and objects of my invention will be more fully understood from the following detail description and the accompanying drawings, in which

Fig. 1 is a side elevation of a telephone receiver having its permanent magnet pro-

vided with poles set at an angle toward each other and a series of sound emitting reeds;

Fig. 2 is a sectional elevation on the line 2—2 of Fig. 1;

Fig. 3 is a sectional elevation on line 3—3 of Fig. 1;

Fig. 4 is an elevation of the series of reeds and mounting means therefor, as viewed from the reverse side shown in Fig. 3;

Fig. 5 is a vertical central section of a modification of my invention adapted to a watch-case receiver or a unit of a radio head-set or loud speaker;

Fig. 6 is a sectional view on line 6—6 of Fig. 5;

Fig. 7 is a vertical central section of a further modification of my invention adapted to a sound-amplifying reproducer; and

Fig. 8 is a vertical central section as viewed at right angles to Fig. 7.

Referring to Figs. 1 to 4 of the drawings, my device comprises the usual receiver shell or casing 10, having the usual removable, perforated head 11. The pole pieces 12, 13 of the permanent magnet 14 are preferably laminated as indicated in Figs. 1 and 2 and secured to the free ends of the respective poles 15, 16 of the permanent magnet 14 by the bolt 17 and spacer 18. The voice-coils 19, 20 are suitably mounted on the respective pole pieces 12, 13. The pins or projections 21, 22 of the shell 10 of the receiver serve to hold the disc or other mounting of the vibratory elements as described more fully hereinafter.

In Fig. 3, 23 represents a disc of preferably non-magnetic material having openings at 24, 25 to respectively fit the pins or projections 21, 22, and further provided with a series of openings 26 corresponding in number to the number of reeds, as will appear. The series of reeds 27 comprise such number of the respective tones of the musical scale and additional reeds as may be desired. Such reeds 27 are of resilient magnetic material and each reed 27 is preferably rigidly attached to the disc 23 by means of an iron rivet 28, extending through the disc 23, and connecting with a bar 29 of magnetic metal as shown in Fig. 3. Such bar 29 is of magnetic metal and of sufficient thickness to maintain permanent engagement with one of the pole pieces, such as the pole piece 12 as shown in Fig. 1. If desired, the bar 29 and the reeds 27 may be formed of one piece, as by stamping, and mounted on the disc 23 in the relation described hereinabove.

Such method of assembly provides a path for the flux of the permanent magnet 14 through the rivets 28 or the bar 29 to the respective reeds 27, and the free ends of the reeds 27 are held in suitable proximity to the other pole piece 13. By reason of the non-magnetic character of the disc 23, there-
65 by having no magnetic influence upon the

flux modified by the voice coils 19, 20, the resilient reeds 27 respond freely through the openings 26 in the disc 23.

Preferably, the reeds 27 are separately attached to the disc 23 and are of such lengths 70 and resiliency as to correspond to the respective notes of the scale of music, so that the composite sound emitted by my receiver is of a harmonic or musical character and free from distortion or imposed sounds set 75 up by the diaphragm of the usual receiver.

In a watch-case receiver or unit of a radio head-set, see Figs. 5 and 6, I prefer to attach the laminated pole pieces 30, 31 of the voice coils 32, 33 to a piece 34 of non-electrically conducting and non-magnetic material of V-shape, fitting between the free ends 36, 37 of the circular magnet 38, and arrange the ends of the pole pieces 30, 31 to directly engage the respective poles 39, 40 85 of the circular permanent magnet 38. The usual watch-case shell is indicated at 42. I prefer to provide the sound emitting perforation 43 of the head 44 of the shell 42 with a strip 45 of felt, suitably held to extend over the perforation 43 in slight taut relation for the purposes and as is set forth in my copending application entitled Modulating diaphragm, Serial No. 712,918, filed by me on the 13th day of May, 1924. 95

The magnet 38 may be removably secured within the shell 42 by the set screws 46, 47.

The series of reeds 48 and a mounting disk 49 of non-magnetic material correspond to the hereinabove described construction and 100 arrangement.

In a sound amplifying receiver, a plurality of permanent magnets 50 may be employed and attached to a common laminated pole piece 51. The extension of magnetic iron 52 is spaced by the recessed, non-magnetic material 52^a, and the same and the pole piece 51 are removably secured to the free ends of the permanent magnets 50 by the bolts 53. Any suitable form of casing 110 54 may be employed, preferably designed to deliver the sound from a drum-shaped cavity, a series of resounding partitions or the usual bridge-supporting sounding boards common violin construction. 115

The series of reeds 55 are similar as hereinabove described and may be mounted on the disk 56 of preferably non-magnetic material. However, as indicated in Fig. 7, each reed 55 may be separately secured to the magnetic extension 52 by individual screws 57. 120

In the above various forms of my invention, it will be noted that I prefer to arrange the pole pieces or the equivalent magnetically acting upon the series of reeds, at an angle to one another, to thereby locate the pole piece which is magnetically spaced from the reeds, more closely toward the free ends of the reeds, and preferably uniform- 125 130

ily from their free ends. Preferably, as is particularly indicated in Figs. 2, 3 and 4 when compared with one another, I arrange the bar connecting the fixed ends of the 5 reeds, to extend in substantial parallel relation to the other pole piece.

From the foregoing, the advantages of my construction and method of operation will be readily understood by those skilled 10 in the art to which the invention appertains.

Whereas, I have described my invention by reference to specific forms thereof, it will be understood that many changes and modifications may be made without departing 15 from the spirit of the invention.

I claim:—

1. In a telephone receiver, an electro-magnet, a set of reeds having a common magnetic base mounted in contact relation with 20 one pole of an electro-magnet, the free ends of said reeds being disposed in magnetic relation to the other pole of said electro-magnet and means for electrically attracting the free ends of said reeds.

2. In a sound-amplifying device, a permanent magnet, a plurality of vibrating reeds in magnetic contact with one pole of said permanent magnet, a disc of non-magnetic material having a plurality of elongated openings for respectively receiving said reeds, an electro-magnet attached to the opposing pole of said permanent magnet, and coil means for operating said reeds by said electro-magnet.

3. In a sound-amplifying device, a plurality of permanent magnets having a common core, means of magnetic material secured to said common core of said permanent magnets in proximity with said electro-magnet, a series of vibrating reeds attached to said means of magnetic material and means for electrically operating said reeds by the core of said electro-magnet.

4. In a sound amplifying device, the combination of permanent magnet means, a set of pole pieces, coil means in electromagnetic relation with said set of pole pieces, a set of attuned reeds disposed in magnetic relation to said set of pole pieces and means of non-magnetic material for fixedly supporting one end of said reeds respectively.

5. In a sound amplifying device, the combination of permanent magnet means, a set of pole pieces, coil means in electromagnetic relation with said set of pole pieces, a set of attuned reeds disposed in magnetic relation to said set of pole pieces and means of non-magnetic material for fixedly supporting one end of said reed respectively, said non-magnetic supporting means being provided with recesses for respectively receiving said reeds and permitting said reeds to vibrate therein.

6. In a sound amplifying device, the combination of permanent magnet means, a set 65 of pole pieces, coil means in electromagnet relation with said pair of pole pieces, a set of progressively attuned reeds disposed in magnetic relation to said pair of pole pieces and means of non-magnetic material for 70 fixedly supporting one end of said reeds relative to one of said pole pieces, the other of said pair of pole pieces extending at an angle to said one pole piece.

7. In a sound amplifying device, the combination of permanent magnet means, a set 75 of pole pieces, coil means in electromagnet relation with said pair of pole pieces, a set of progressively attuned reeds disposed in magnetic relation to said pair of pole pieces and means of non-magnetic material for 80 fixedly supporting one end of said reeds relative to one of said pole pieces, the other of said pair of pole pieces extending at an angle to said one pole piece and substantially parallel to 85 the free ends of said set of reeds.

8. In a sound amplifying device, the combination of permanent magnet means, a set 90 of pole pieces, coil means in electromagnet relation with said pair of pole pieces, a set of progressively attuned reeds disposed in magnetic relation to said pair of pole pieces and means of non-magnetic material for 95 fixedly supporting one end of said reeds relative to one of said pole pieces, the other of 95 said pair of pole pieces extending at an angle to said one pole piece and substantially parallel to the free ends of said set of reeds, said non-magnetic supporting means having 100 openings of progressive length respectively receiving the reeds of progressive length of said set of reeds.

9. In a sound amplifying device, the combination of permanent magnet means, a set 105 of laminated pole pieces, coil means in electromagnetic relation with said set of pole pieces, a set of attuned reeds disposed in magnetic relation to said set of pole pieces and means of non-magnetic material for fixedly supporting one end of said reeds respectively. 110

10. In a sound amplifying device, the combination of permanent magnet means, a set of laminated pole pieces, coil means in electromagnet relation with said pair of pole pieces, a set of progressively attuned reeds 115 disposed in magnetic relation to said pair of pole pieces and means of non-magnetic material for fixedly supporting one end of said reeds relative to one of said pole pieces, the other of said pair of pole pieces extending at an angle to said one pole piece and substantially parallel to the free ends of 120 said set of reeds.

In testimony whereof I have signed this specification this 11th day of February 1925.

DE ELBERT A. REYNOLDS.
